FIG. 1 is a perspective view of a combined lid, hinge and upper portion of a refuse container showing the new design; FIG. 2 is a side elevational view thereof, the opposite side being a mirror image;

FIG. 3 is a side elevational view thereof, with the hinge in open position, the opposite side being a mirror image; FIG. 4 is an enlarged top perspective view thereof, showing the internal design of the hinge, with the body and lid shown fragmented for ease of illustration; and,

FIG. 5 is a sectional view taken along line 5—5 of FIG. 1 with lid and body shown fragmented for ease of illustration. The broken line showing of a container and wheels is for illustrative purposes only and forms no part of the claimed design.
